CLYMER JACOBS, OF SAN DIEGO, CALIFORNIA

BED COUPLING

Application filed May 27, 1930. Serial No. 455,985.

My invention relates to bed couplings, and the objects of my invention are:

First, to provide a bed coupling which enables a bed to be assembled or disassembled without the aid of tools;

Second, to provide a coupling of this class adapted to join the side rails of a bedstead to a bed head and bed foot, and which cannot stick or bind, as the necessity of a wedging joint is eliminated;

Third, to provide a bed coupling in which the one member thereof may be formed integral with the bed head or bed foot, or may be constructed as a fitting to be secured to these members;

Fourth, to provide a coupling of this class which holds the bed from giving way diagonally so that the bed retains its proper rectangular form; and

Fifth, to provide on a whole a novelly constructed bed coupling which is particularly simple of construction, proportional to its functions, durable, efficient in its action, and which will not readily deteriorate or get out of order.

With these and other objects in view as will appear hereinafter, my invention consists of certain novel features of construction, combination and arrangement of parts and portions as will be hereinafter described in detail and particularly set forth in the appended claim, reference being had to the accompanying drawings and to the characters of reference thereon, which form a part of this application, in which:

Figure 1 is a perspective view of the one member of my coupling; Fig. 2 is a fragmentary perspective view of the other member of my coupling; Fig. 3 is a similar perspective view of a slightly modified form of coupling member; Fig. 4 is a reduced fragmentary perspective view showing the corner of a bed and my coupling incorporated therewith; Fig. 5 is a fragmentary plan view of my coupling in its one form, with the por-

tions thereof broken away and in section; and Fig. 6 is a fragmentary sectional view thereof through 6-6 of Fig. 5, with parts and portions shown in elevation.

Similar characters of reference refer to similar parts and portions throughout the several views of the drawings.

My coupling comprises a socket member 1, which is provided with a flat base portion 1a adapted to be secured at its upper and lower ends to a bedpost A of the bed foot or bed head member B, as shown in Fig. 4. Extending outwardly from the base portion 1a, at right angles thereto and flush with each side thereof, is a bracket 1b. Each bracket 1b extends vertically, that is, longitudinally with the base 1a, and terminates near the ends of said base so as to form ear portions 1c. These ear portions have openings 1d therein, whereby the socket member may be secured to the bedpost A.

Each bracket 1b is provided with an in-turned end portion which extends toward the other bracket, as shown best in Fig. 1. These extended portions 1e form therebetween a narrow vertically disposed slit 1f. The two brackets 1b and extended portions 1e define a vertically disposed socket 1g open at its ends and intersected by the slit 1f. The socket 1g is substantially square in cross-section and is of constant diameter.

The other member of the coupling is formed at the ends of the bed side rails 2. One form of this coupling is shown in Figs. 2, 5, and 6, while a second form is shown in Figs. 3 and 4. In the form shown in Figs. 2, 5, and 6, the bed rail is in the form of an angle iron, that is, L-shaped in cross section at each end; the downwardly or vertically extending wall thereof increases in depth, as indicated by 2b, and is provided at its end with an integrally, vertically disposed block or enlargement 2c, which is adapted to fit in the socket 1g, as shown in Figs. 5 and 6. The block portion 2c, which extends the length

of the socket 1g, may be hollow, as shown in Fig. 6, in order to lighten the structure. The block 2c is of constant diameter throughout its length, and forms a loose enough fit with the socket 1g so that it cannot possibly wedge therein.

Formed integrally with the block 2c at its upper end is a cross position 2d, which overhangs either side of the block 2c, but is flush with the extended end thereof. The overhanging portions 2e are adapted to rest on the upper ends 1h of the brackets 1b. The cross portion extends rearwardly from the block 2c and is offset to one side so as to merge into the horizontally disposed portion 2f of the bed side rail, as shown best in Figs. 2 and 5.

The structure shown in Figs. 3 and 4, is adapted for bed side rails of a T-shaped cross section. The vertically disposed portion or leg 3a of each bed side rail is increased in depth at its ends, as indicated by 3b, and joins the rear side of vertically disposed blocks 3c, similar to the blocks 2c. Likewise the block 3c is provided with a cross portion 3d at its upper end. This cross portion 3b forms a continuation of the horizontal or cross portion of the bed rail 3. The block 3c likewise fits into the socket 1g and is prevented from passing therethrough by the overhanging portions 3d of the cross portion 3b.

It can be seen that the coupling thus formed by the members 1 and 2, or 1 and 3, holds the parts of the bed in rigid and firm relation when in use. However, when desiring to assemble or disassemble the bed, it is necessary only to raise the side members 2 and 3 vertically in order to disengage them from the head and foot members of the bed.

It is obvious from the construction as illustrated in the drawings and described in the foregoing specification that there is provided a bed coupling as aimed at and set forth in the objects of the invention, and though I have shown and described a particular construction, combination and arrangement of parts and portions, and a certain modification thereof, I do not wish to be limited to this particular construction, combination and arrangement, nor to the modification, but desire to include in the scope of my invention the construction, combination and arrangement substantially as set forth in the appended claim.

Having thus described my invention, what I claim as new and desire to secure by Letters Patent is:

In a bed coupling, an integrally formed bed side member including a vertically disposed web portion, and a horizontally disposed strip, said web portion and strip joined along their one margins for the major portions of their lengths, said horizontally disposed strip offset laterally at its ends por-

tions so as to assume a centered relation with said web portion, and a vertically disposed enlargement of constant diameter at each end of said web portion abutting an offset portion of said strip so as to form a shoulder therewith, and a coupling member arranged to coact with said enlargement and said shoulder so as to interlock therewith.

In testimony whereof, I have hereunto set my hand at San Diego, California this 21st 75 day of May, 1930.

CLYMER JACOBS.
